FURNACE WALL CONSTRUCTION

Philip Washington Antill, Ridgefield Park, N. J.,
assignor to American Arch Company, New
York, N. Y., a corporation of Delaware

Application July 17, 1933, Serial No. 680,716

20 Claims. (Cl. 72—101)

This invention relates to wall construction and more particularly to refractory furnace wall structures, and is especially concerned with metallic supporting, securing and maintaining means or elements, such as hangers, tie bars, gripping elements, and the like, particularly adapted to the support and positioning of belts or zones of blocks of a wall structure or refractory bricks of a furnace wall of the sectional type, wherein the structure may comprise a plurality of vertically superposed, horizontally extending, individually supported, and separately expandable wall sections, each section of which may be made up, if desired, of a plurality of courses of bricks.

Specifically, the invention relates to metallic supports or hanger means, adapted for engagement with an exterior supporting structure, such as the outer wall of a double or hollow furnace wall construction, for hanging or supporting the refractory or inner wall, in sections, therefrom; and tie bars or brick engaging means adapted to cooperate with such hangers for the lateral positioning or retention of the bricks as against dislodgment. In other words, the present invention relates primarily to the metallic supporting and retaining parts of a sectionally supported wall, and especially to certain particular forms of brick hangers and tie bars, or similar metallic parts, of several different types, some of which are adapted to be readily interchangeable, that is, capable of substitution one for another, and all of which are adapted for ready replacement, renewal, inspection or repair; the present application containing matter divided from, and being a continuation, in part, of my prior filed, but copending, applications, identified as follows: application on Furnace wall construction, Serial No. 152,768, filed December 6, 1926, issued Sept. 26, 1933 as Patent No. 1,927,909; application on Furnace walls, Serial No. 170,202, filed February 23, 1927, issued December 19, 1933 as Patent No. 1,939,646; and application on Refractory furnace walls, Serial No. 547,047, filed June 26, 1931, issued September 4, 1934, as Patent No. 1,972,838.

In a general way, the primary objects of the invention include: the improvement of hollow furnace walls of the sectional type; the provision of such walls of less difficulty of construction and repair, and, at the same time, greater stability and strength than those heretofore commonly in use; the direct utilization of the primary strength members of the outer or supporting wall portion in the supporting structure for the inner wall; the provision of an improved wall structure capable of ready installation in sections and of easy re-

newal as to the sections thereof and as to the individual parts of each section; provision for proper cooling of the wall and the supporting structure thereof; the provision of novel types of supporting means including hanger or tie bar means, and more specifically, the further provision of such metallic members arranged to be disposed entirely outside of the refractory wall itself; the improving of sectionally supported walls from the standpoint of construction, erection, repair and inspection; and the accomplishment of the foregoing purposes in large part by improved forms of metallic hangers and tie bars for wall construction.

The nature, objects and advantages of the present invention may perhaps be more clearly understood after a brief reference to prior art practice. Such prior practice has contemplated a sectional wall in which each horizontally extending belt or section of the wall was composed of a plurality of laterally adjacent, aligned, vertical tiers of bricks, with the bricks of each tier having slots threaded on to a vertical flange or flanges of an upright bar, which latter had upper and lower outwardly projecting arms for support from and positioning by an outside structure; in which wall construction the bars of alternate wall sections had to be laterally offset, relative to each other, so as not to cause interference between the vertical bars of one horizontal wall section and the vertical bars of the next superjacent and subjacent horizontal wall sections. Among the difficulties of such prior practice were the problems of brick replacement and supporting-bar replacement, since the burning out of one brick of a tier, adjacent the lower portion of a section, would necessitate removal from the bar of all the superjacent bricks of that tier; while the replacement of a bar itself necessarily involved the disturbance of the entire vertical tier of bricks carried by such bar. Likewise, damage to a brick retaining flange, or to the foot member of a bar (on which the tier was supported) necessitated replacement of the entire bar.

The present invention involves separate, but cooperating, vertical bars or hanger members, and horizontal bars or brick engaging members; the provision of hanger members, each of which engages the outer wall structure only at the upper end of the hanger member, the lower end of the member being made for cooperation with and lateral support against a similar subjacent hanger member; the provision of a special type of divided hanger member, for ease of assembly and repair; the provision of interengaging hangers

and brick tie bars, particularly by a construction of tie bar which is capable of embracing or removably engaging either a single hanger member or a plurality of them; the interfitting of the 5 hanger members and tie bars in such manner that some freedom for relative movement, particularly in a vertical direction, is provided, not only to care for expansion and contraction of the refractory wall, but also to provide for the ready 10 replacement of bricks and tie bars, and to make possible the utilization of bricks of different vertical thickness; employment of brick tie bars in such manner as to make the lateral support or 15 positioning of the bricks independent of their vertical support on the feet of the hangers, and the supporting of the said tie bars laterally by means of the hangers and vertically by means of the bricks themselves; the provision of such tie bars arranged to secure or retain a single brick 20 or a plurality of bricks, and either in one row or course of the section or in a plurality of rows or courses; the provision of hanger and tie bar members which cooperate with the bricks in such 25 manner as to permit not only relative adjustment between the sections of the wall but also some freedom for expansion between individual bricks of a section, and some freedom of adjustment or movement between the bricks and the metallic elements; and the construction of the tie bars 30 and hangers in such manner that certain bricks of a section may receive support from a plurality of hangers, or that a plurality of bricks, either laterally or vertically considered, may receive support from a single hanger.

35 By such features of the invention, together with other details of construction which will hereinafter appear, I not only obviate the disadvantages of the prior art, such as hereinbefore mentioned, but also attain numerous advantages, 40 among which might be mentioned: the possibility of placing the bricks of the several courses of a wall section in alternately staggered arrangement, so as to have broken joints (viewed from the inner face of the wall); the practical feasibility 45 of having irregular joints between the laterally abutting faces of adjacent bricks of a course, to facilitate expansion and contraction, while maintaining the wall tight as against ingress of air or egress of gases; the possibility of 50 reducing the number of hangers necessary for a given wall area, and tying fewer of the bricks to the hangers for lateral support, since the irregular joints between abutting faces of adjoining blocks may be utilized for lateral support of certain of the blocks.

55 How the foregoing and other objects and advantages such as may be incident to the invention or as may occur to those skilled in the art are attained, will be evident from the following 60 description, taken in the light of the accompanying drawings, in which drawings:—

Figure 1 is an elevation of a portion of a horizontally extending belt or zone of a vertical furnace wall or refractory lining, illustrating one 65 embodiment of the improved supporting means or hangers and retaining means or tie bars, with the refractory bricks or blocks in supported or retained position; Figure 2 is a plan view taken on the line 2—2 of Figure 1, more clearly illustrating the metallic parts, making up the present invention, with the three upper rows of bricks of the section removed; and Figure 3 is a fragmentary, somewhat enlarged, view taken approximately on the line 3—3 of Figure 1, with certain 70 parts broken away and others shown in section,

and showing also the interrelation between the lower part of an upper wall section and the upper part of a subjacent wall section, Figures 1 to 3 thus illustrating one general embodiment of the invention;

5 Figures 4 and 5 are views somewhat similar to Figures 2 and 3, but illustrating a modified form of the hanger and tie bar mechanism, Figure 4, however, illustrating an opposite wall face, as compared with Figure 2; and Figure 6 is an enlarged plan view of one of the tie bars shown in Figures 4 and 5; these three figures constituting a second embodiment of the invention;

10 Figure 7 is a view similar to Figures 2 and 4, but illustrating a third embodiment of the invention; and Figure 8 is a view approximately on the line 8—8 of Figure 7, and showing the relationship of the adjacent wall sections of this embodiment, in a manner similar to the illustration of Figures 3 and 5;

15 Figures 9, 10 and 11 illustrate a fourth general embodiment of the invention; Figure 9 substantially corresponding to Figure 7, and being taken on the line 9—9 of Figure 10; Figure 10 being a view substantially corresponding to Figure 8, and being taken on the line 10—10 of Figure 9; and Figure 11 illustrating a half-bar tie member, which may be substituted, in appropriate locations, for the tie members seen in Figures 9 and 10.

The first embodiment of the invention

20 Referring first to Figures 1 to 3, it will be seen that I have therein illustrated part of a hollow or double furnace wall, having a solid or fixed outer portion 2, which may be of any suitable construction, and an inner refractory portion 3 supported therefrom, with an air space 4 between the two; the outer wall or wall portion 2 having structural members such as horizontally extending steel beams 2a; although it should be understood that the sectional refractory wall 3 may be supported simply from a suitable structural work (such as 2a) per se, if a hollow or double wall arrangement is not required.

25 Figure 1, which is a view of the refractory wall, from the inside of the furnace, illustrates a portion of a horizontally extending belt or section, which section, in the embodiment shown, comprises a series or course of supporting bricks 35 or base blocks 13, and preferably a plurality of alternate rows or courses composed, respectively, of tied and filler blocks 18, 18a, and of intermediate blocks 17; the section being topped off by a course or row of L-shaped blocks 19 adapted 40 to make a vertically sliding joint at 20 with the base blocks 13 of a superjacent wall section, smaller blocks 21 and a sand or other seal 22 being provided in the gap between the L-blocks 19 of a subjacent section and the blocks 18, 18a, 45 in the next superjacent section. Such an arrangement of blocks in each section, and relative arrangement between the sections, forms a part 50 of the invention covered by my aforementioned copending application Serial No. 152,768.

55 The metallic hanger and tie bar elements, of the present invention, cooperate to vertically support and laterally retain such a wall section, and to interfit with similar metallic elements of superjacent and subjacent sections, in the following manner:

60 For each wall belt or section there is a horizontal row of vertically extending supporting castings or hanger members 5, each of which has, at the top, an outwardly extending head portion 75

8, formed with a groove or slot 6, preferably of wedge shape and reenforced by laterally extending flanging 7, for direct engagement with the flanges of the main structural work or beams 2a. 5 Each hanger 5 further has a pair of lateral flanges forming a cross web 16, extending along the major portion of the length thereof, and carries at the bottom a foot 9, which, together with the base of the main web 10 of the hanger and 10 the lateral bracket-like portions 11, forms a pair of pockets or recesses 12, adapted to receive and support the base blocks 13, and to retain them in position at each side of the main vertical web 10. An indentation or other suitable 15 face portion 14 at the back of the foot of each hanger is positioned to bear against a shoulder 15 on the subjacent hanger, for lateral support and positioning.

From the foregoing it is clear that a wall section is supported on a series of base blocks 13 carried on the shelf or foot means 9 of a series of hangers 5. The spaces 12, into which the ends of the base blocks 13 fit, and which I may term "pockets", or more broadly "recesses", are 20 preferably formed of such a height, between the bottom surface of the plate or bracket-like portions 11 and the top surface of the foot or shelf means 9, as to form a relatively snug fit with the ends of the base blocks 13, so that said blocks 25 cannot tilt downwardly toward the inner side of the furnace under the weight of the superimposed bricks of the section. In other words, the base blocks 13 (as best seen in Figure 3) are maintained by the plates 9 and 11, as against 30 tilting under the weight of the superimposed blocks which are carried by the base blocks. Thus the blocks of a section receive proper vertical support, in a level position.

For the retention of the tied or secured blocks 18, as against lateral displacement, I provide tie members 23, 24, each of which has a pair of depending lugs 25 engaging sockets or vertical holes 26 in the ears 27 of the said bricks 18. The tie members or bars 23, which are alternated, vertically, with the ties 24, are of such a length as to engage the lateral flanges 16 of adjacent hangers 5, and the shorter tie bars 24 are kept in their proper position (with the bricks which they engage) and supported as against lateral displacement, by the vertical rods 28, each of which rods extends through one vertical series of the alternating tie members 23, 24, and rests at the bottom upon one of the blocks 13.

Blocks 18a, not so tied, are positioned in pairs between pairs of tied blocks 18, and secured as against lateral displacement by means of the irregular joints between the abutting faces of laterally adjacent blocks, for example by means of the recesses 29 and the shoulders 30. Mating faces of each pair of blocks may also be recessed as at 31, for the reception of insulating material, such as asbestos or the like.

From the foregoing it is clear that my improved hanger and tie bar elements are not only well adapted to retaining the advantages incident to sectionally supported and sectionally expandable and renewable furnace wall construction, but are also of material and novel advantage in providing for the greatest ease and the lowest cost in initial installation, repair, inspection, and replacement, in assuring the adequate shielding of the metallic parts from the furnace heat, in providing unusually clear and unobstructed room for circulation of air around the metallic parts for cooling them and for preheating the air, and in

obtaining a proper alignment and retention not only of the refractories themselves but also of the metallic elements, which latter are well adapted for adjustable locating for differences in spacing between hangers, for differences in spacing between the beams 2a on which the hangers are carried, for differences in length and height of bricks employed or wall sections used, and for different desired arrangements of the bricks in a section.

5

10

The second embodiment of the invention

In the second form of the invention, which involves advantages similar to the first, I further simplify the metallic supporting and retaining elements, while at the same time reducing the number of different parts employed as well as reducing the total number of tie bar elements required for a given wall area. As before, the brick work may take various forms, but for purposes of illustration, I have shown a refractory construction in Figure 5 similar to that before discussed, and as it is not per se a part of the present invention it need not here be further described.

15

20

25

The hanger members 5a are in general similar to hangers 5 in the first form, but I provide the foot or shelf means 9a thereof with grooves or slots 32 extending longitudinally of the wall, which leave upstanding ribs 33, tending to provide a more stable support for the base blocks 13, which may have some irregularity or warping in their construction. Alternatively, the grooves 32 may be utilized for a supporting metallic base strip for the base blocks 13, as will be later described in connection with the third embodiment of the invention.

30

35

In place of the elements 23, 24 and 28 for tying the bricks (as in Figures 1 to 3) I employ a single form of element 23a (illustrated in Figure 6). 40 This element instead of being located between a pair of hanger bars, straddles or embraces the outer edge of the hanger, and preferably has recesses 34 cut in the two bar portions 35, 35 (which together form one tie bar) to slidably engage the main vertical web 10 of the hanger. The two bar portions 35 are joined together, and in fact may be cast integral with two upstanding webs 36.

45

The single tying unit, thus formed, has two lugs or pins 37 extending upwardly and two extending downwardly, and the bar unit as a whole is curved or bent, approximately into the shape of a V, and the lugs are mounted on the forwardly extending arms of the V, in position to be interengaged with the aperture 26a of the tied bricks. 55

50

55

The third embodiment of the invention

In this form of the invention, as seen in Figures 7 and 8, the refractories and the outer or supporting wall structure may be similar to those heretofore shown, since these do not per se form part of the present invention, but for the sake of illustrating the adaptability of the various hangers and tie bars, I have disclosed a modified type of tied block 18b; also modifications in the L-blocks 19a, cap blocks 21a and seal 22a and 22b. I have also illustrated a different shape of base block 13a, although it should be understood that base blocks similar to those hereinbefore described may be employed.

60

65

70

The hanger members 5b may, as shown, cooperate with a different form of supporting beam 2b, and, in general, the upper ends of these hangers are similar to those hereinbefore described; but at their lower ends they are formed 75

with pockets or recesses 12a of a modified shape and differently located, as compared with those heretofore discussed. In this form of hanger, the foot 9b, instead of extending forwardly into the wall, terminates at the rear face of the block 19a, and it is joined to the upper plate 11 by a rear wall 38, instead of by an extension of the main web (as at 10 in the prior constructions). In the recess 32a I may place a supporting metallic strip 39, which may extend straight through for support on several hangers. Thus the base block 13a may run straight through, from one side of the hanger to the other, or a series of small base blocks may be used, since some of them may receive part of their support from the metal shelves or strips 39.

An extremely simple bent tie bar 23b may be used with this construction, straddling the rear of flange 10 of the hanger, and having only two lugs, which may be in the form of downwardly bent arms 40, for engagement with the bricks.

In this type of construction, the rear wall 38 of the socket of one hanger abuts against the shoulder 15 of the next hanger, for positioning and for support transversely of the wall. Although the metallic parts of this form of the invention may be made to be interchangeable with parts of the previously described embodiments, this form has an added advantage over the prior forms in that the full normal thickness of the refractory furnace wall is interposed, at all points, between the inner face of the wall and the metallic parts. Thus no metallic part of the supporting and retaining structure is extended into the refractory wall itself, and no such parts are closer to the inside of the furnace than the full thickness of the refractory bricks.

The fourth embodiment of the invention

40 The metallic structures of the fourth embodiment, shown in Figures 9 to 11, although of a more built up nature, and thus more readily facilitating replacement of parts, are just as stable in their support and securing of the refractories, 45 and are equally adaptable to the various refractory arrangements. The refractories shown in these views are similar to those illustrated in association with the third form, and need not here be further described.

50 The hangers, indicated generally at 5c, are each made in two pieces, to wit: a bracket part 41 and a vertical bar part 42. The bracket element 41 is generally triangulated in nature, not only for strength but for other purposes, as hereinafter brought out.

The bracket 41 has a rear hook 6a for engagement with a beam 2b, and a front hook or recess 43, preferably flanged at 44, for wedgingly guiding and receiving the lateral lugs or abutments 45 on the main web 10 of the hanger bar 42. The element 41 is also preferably lightened by an aperture 46, and is provided with a front flange 47 and a top flange or shelf means 48. The front flange serves to position and laterally support the rear wall 38 of the foot portion of a superjacent hanger; and the top flange 48 serves to position and support the dividing partitions or baffles 49, which serve to separate the air space 4a into a series of air passages, between the outer and inner walls.

70 Each hanger bar 42, when supported by its bracket portion 41, serves to carry one or more bricks 13a of a section, by means of a socket-like pocket or recess 12b, which is formed by the upper and lower plates 11 and 9b, the rear wall 38,

and the dividing web or downward extension 10a of the main hanger web 10. Although the main web may thus be carried down, as indicated at 10a in Figure 10, and connected integrally with the bottom shelf or foot 9b, the lateral flanges 16a of the hanger terminate (as in the prior constructions) just above the base block 13a.

The tie bars 50, of this construction, instead of being bent to embrace the outside edge of the main web 10, are substantially straight and each 10 such bar has an upstanding stiffening web 51 which may lie against the inner side of the hanger, and hook-like portions or webs 52 which embrace the flanging 16a of the hanger. The tie bar may thus be slipped over the end of the 15 hanger member, with the downwardly projecting tie bar lugs 53 extending into the apertures 54 of the bricks.

For use adjacent corners of the furnace, or in any other place where an individual tie bar for 20 a single brick is desired, I may cut off such a bar, or provide a single ended bar, such as shown in Figure 11. It will readily be seen that with either the single or double ended construction, removal of a tied brick may be accomplished by 25 simply slipping the tie bar upwardly along the hanger flanges until the lug 53 is clear of the brick aperture, and then pulling or knocking the brick out of the wall; it being possible to do this without disturbing the other bricks, if 30 desired, since the staggered arrangement of bricks assures a support for those bricks which surround a brick that is being replaced.

From all of the foregoing it will now be evident that the invention involved in the various forms 35 of my metallic hanger members and tie bars goes far toward removing the disadvantages and problems of the prior art and attains all of the objects and advantages hereinbefore stated. It will furthermore be seen that the several forms 40 of supporting hangers may be used with various arrangements of refractories, and so also may the various forms of tie bars; and that the several different forms of tie bar mechanism may be employed with any one of the types of hanger 45 members, the T-shaped cross sectional form of the hangers being well adapted to the aligning and outside lateral support of the refractories, as well as for cooperation with either the spanning or the embracing or the gripping type of tie 50 bar. In addition, these metallic parts may be chiefly made, as integral castings, of iron, steel, or other metal.

I claim:—

1. For a sectionally-supported multi-block wall, 55 a metallic hanger member comprising a main body part with means formed to secure the same on a support, and a plurality of vertically spaced-apart block engaging portions, the lower of said portions being positioned to give vertical support 60 to a block and the upper of said portions being extended laterally from the main body part to overlie and engage an upper portion of the same block whereby to hold the block on said lower portion as against tilting of the block.

2. For a sectionally-supported multi-block wall, 70 a metallic hanger member comprising a vertically elongated main body portion, means adjacent the upper end thereof formed to hangingly engage a support, and means adjacent the lower end thereof formed to provide a laterally open recess for embracingly engaging a wall block.

3. For a sectionally-supported multi-block wall, 75 a metallic hanger member comprising a vertically elongated main body portion, means adjacent the

upper end thereof formed to hangingly engage a support, means adjacent the lower end thereof formed to support a wall block, and hanger abutting means also adjacent the lower end thereof positioned and adapted to engage an upper portion of a similar subjacent hanger for receiving lateral support therefrom.

4. For a sectionally-supported multi-block wall, a metallic hanger member comprising a vertically elongated main body portion, means adjacent the upper end thereof formed to hangingly engage a support, means adjacent the lower end thereof formed to support a wall block, and hanger positioning means adjacent the upper end thereof formed as an abutment to engage and laterally support a lower portion of a similar superjacent hanger.

5. For a sectionally-supported multi-block wall, a metallic supporting member for blocks of a section comprising a body portion with means for securing the same to a support, and upper and lower block engaging portions positioned in spaced-apart relation and extending laterally to form recess means therebetween for receiving portions of a plurality of adjacent blocks of a horizontal course, the said lower portion lying approximately horizontally to provide vertical support for such blocks and the said upper portion being positioned to overlie an upper face of such blocks whereby to hold them in seated position on said lower portion.

6. For a sectionally-supported multi-block wall, a metallic supporting member for blocks of a section comprising a body portion with means for securing the same to a support, and upper and lower block engaging portions positioned in spaced-apart relation and extending laterally to form recess means therebetween for receiving portions of a plurality of adjacent blocks of a horizontal course, the said lower portion lying approximately horizontally to provide vertical support for such blocks and the said upper portion being positioned to overlie an upper face of such blocks whereby to hold them in seated position on said lower portion, and the main body portion being also elongated in a vertical direction with a substantially flat face adapted to abut and position superposed courses of blocks when placed on said first mentioned course.

50 7. A metallic hanger member of the character described, comprising a vertically elongated main body portion of substantially T-shaped cross section, means adjacent the top thereof formed to hangingly engage a support, and a plurality of horizontally extending block engaging plate means formed thereon at vertically spaced-apart locations.

8. A hanger for the support of bricks of a refractory wall having suspension means at its upper end, brick supporting means at its lower end, and means for engaging another hanger.

9. For a sectionally-supported multi-block wall, a divided hanger member, one part of which comprises a substantially vertically elongated bar member and the adjoining part of which comprises a bracket or frame member, the first mentioned part having a readily separable hanging connection from the second mentioned part, and the second mentioned part having means of movable interlocking fit with a supporting structure.

10. For a sectionally-supported multi-block wall, a divided hanger member, one part of which comprises a substantially vertically elongated bar member and the adjoining part of which comprises a bracket or frame member, the first men-

tioned part having a readily separable hanging connection from the second mentioned part and having means adjacent the bottom for supporting a wall block, and the second mentioned part having means of movable interlocking fit with a supporting structure.

11. For a renewable wall structure, a metallic hanger member having means whereby it may be supported in upright position adjacent to the outer face of a multi-block wall, said member having a laterally open socket formed with upper and lower elements adapted to receive and engage a portion of a wall block for gripping support thereof.

12. For a sectionally-supported multi-block wall, a metallic hanger member comprising a vertically elongated main body portion, means adjacent the upper end thereof formed to hangingly engage a support, shelf-like means adjacent the lower end thereof and formed to support a block of the wall, and a recess or grooving in such shelf means.

13. For a multi-brick wall of the type which is sectionally supported by vertical hangers or the like, a brick retaining tie bar comprising a substantially horizontally elongated metallic body portion with means of vertically sliding engagement with a hanger and having vertically extending brick-engaging lug means longitudinally offset from said means of hanger engagement.

14. A horizontal tie bar, for bricks of furnace wall construction, having a pair of vertically-extending brick-engaging lugs and its end portions extended therebeyond with means for engagement with a wall-supporting member.

15. A tie member for furnace wall blocks, comprising a pair of bar-like portions having web means between them, and block-engaging lug means on said bar portions, said portions being bent in a horizontal plane to engage part of a vertically-extending wall supporting structure.

16. A tie-member, for laterally securing a furnace wall structure to a vertically extending supporting structure, comprising a substantially elongated body portion, which is relatively narrow in its overall transverse dimension, having three elements for vertically sliding engagement with associated structures, a pair of said elements being located adjacent the ends of the body, and one intermediate the ends, whereby the pair may engage one of said structures, and the intermediate one may engage the other structure, for lateral interlock of the two structures.

17. For sectional furnace wall construction having vertically spaced horizontally extending supporting elements, a readily removable divided hanger member for cooperation with a supporting element, one part of which is a substantially vertical elongated bar member, and the adjoining part of which is a substantially triangular frame member, the said two parts having interlocking sockets, and the first of said two parts having adjacent the base a brick receiving socket.

18. For sectional furnace wall construction having vertically spaced horizontally extending supporting beams, a divided hanger member, one part of which is a substantially vertical elongated bar member, and the adjoining part of which is a substantially triangular frame member, the said two parts having interlocking sockets, the said triangular part having an upper and outer point of triangulation provided with a support engaging element for co-operation with a supporting beam.

19. A hanger or bracket, for the support of

blocks of a refractory wall, having means formed thereon to hangingly engage a support and having means formed thereon to provide a laterally open recess or pocket shaped to receive a portion of a wall block, said pocket having superimposed faces with the bottom block-supporting face located adjacent the level of the bottom of the pocket opening.

5 20. A metallic wall-brick-supporting bracket

for a sectionally supported refractory wall, said bracket having support means whereby it may be carried by a member external to the refractory wall and having a plurality of superposed plate-like elements extending laterally to underlie and overlie a block of said wall for effecting a rigid support of such block and any superjacent blocks which may be carried thereon.

PHILIP WASHINGTON ANTILL.
